UNITED STATES PATENT OFFICE.

CHARLES B. TEWKSBURY, OF BOSTON, MASSACHUSETTS, ASSIGNOR TO SECURITY TAG COMPANY, OF BOSTON, MASSACHUSETTS, A CORPORATION OF MAINE.

TAG.

1,127,112.

Specification of Letters Patent.

Patented Feb. 2, 1915.

Application filed May 4, 1910. Serial No. 559,347.

To all whom it may concern:

Be it known that I, CHARLES B. TEWKSBURY, a citizen of the United States, residing in Boston, county of Suffolk, and State 5 of Massachusetts, have invented an Improvement in Tags, of which the following description, in connection with the accompanying drawings, is a specification, like letters on the drawings representing like 10 parts.

This invention relates to a shipping or like tag of that class in which one or more strings or like flexible attaching devices are extended longitudinally of the tag between the 15 two layers or sheets thereof.

The invention has for one of its objects to provide a superior tag of the character specified, in which, preferably provision is made for obtaining a flat, unbroken surface 20 for printing and addressing purposes. Further, in the preferred form of my device the string is locked against longitudinal and lateral movement at its free end, thereby reducing to a minimum the danger of the 25 layers of the tag being separated by lateral movement of the free end of the string, and also of the tag being rendered useless by one of the layers being torn or split longitudinally as will be described. These and 30 other objects of my invention will be hereinafter referred to and the novel combinations of elements whereby said objects may be attained will be more particularly pointed out in the claims at the end of this 35 specification.

Figure 1 is a plan of one form of tag embodying this invention. Fig. 2, a plan of the tag shown in Fig. 1 inverted. Fig. 3, a cross section on the line 3—3, Fig. 2. Fig. 4, a 40 cross section on the line 4—4, Fig. 2, and Fig. 5, a detail in cross section of the tag shown in Fig. 2 with the parts separated.

The tag herein shown as embodying this invention is composed of two superimposed 45 layers *a*, *b*, of paper or other suitable material, which are cemented or gummed or otherwise secured together and between which one or more strings, wires or other flexible attaching devices *c* are located. In 50 the present instance, two spring *c* are represented as extended longitudinally of the tag between the layers *a*, *b*, thereof, and one of the features of the present invention consists in providing a tag having the longitudinally extended springs or flexible de-

vices *c*, with a flat, unbroken surface for printing or addressing purposes like the ordinary tag (not shown) but which is provided at one end with an eye for the attachment of the string.

In order to provide for the flat, unbroken surface of a tag having a longitudinally extended string or strings *c*, one of the layers as *a* is provided with a longitudinally extended groove *d* formed in it, for the reception of the said string. The groove *d* may and preferably will be provided with curved side walls 10, 12, which conform in shape to the form of the strings *c* and thereby increase the surface contact between the 70 layer *a* and the strings, with the result that a firmer and better engagement of the strings with the layers of paper is obtained, and the curved side walls of the groove serve as locking devices for the string against lateral movement at or near the free ends of the strings, thereby reducing to a minimum the danger of the separation of the layers *a*, *b*, by lateral movement of the free ends of the strings.

Provision may also be made for reinforcing the tag transversely and for locking the strings against movement tending to strip them from one or the other of the layers thereof, whereby the danger of designedly 85 or inadvertently destroying the tag is prevented. To this end, I employ preferably two transversely extended threads or other flexible devices 20, 21, located between the layers *a*, *b*, one above and the other below 90 the longitudinal strings *c* as clearly represented in Fig. 5.

The transverse strings 20, 21 are secured to the inner surfaces of the layers *a*, *b*, by the cement or other adhesive substance employed to secure the layers *a*, *b*, together, and the transverse string 20 is provided with the portion 23 arched in conformity with the shape of the groove *d*, and this arched portion also serves to reinforce the 95 side walls of the groove and prevent separation of the layers *a*, *b*, by lateral movement or strain on the free ends of the longitudinal strings *c*.

The transverse reinforcing devices or 105 threads 20, 21, which are and may be materially thinner than the longitudinally extended strings *c*, are located above and below said longitudinal strings and serve as locking devices or stops for said strings, and 110

thereby prevent either or both layers *a*, *b* being torn or split by pulling the strings *c* longitudinally of the tag.

By reference to the drawing, it will be seen that if the strings *c* or either of them are attempted to be moved longitudinally of the tag, they are arrested by one thread, as 20, if the tear is started in the layer *a* and by the thread 21 if the tear is started in the 10 layer *b*.

The transverse reinforcing devices may be threads, fine wire or other suitable material.

While I prefer to incorporate the transverse threads in a tag having one of its layers grooved longitudinally for the reception of the attaching string or strings, I do not desire to limit the invention in this respect.

20 The layers *a*, *b*, may be formed from two separate sheets or layers, but herein, also, the invention is not to be regarded as being limited to such construction.

Claims.

25 1. A tag of the character described, comprising layers of paper or like material secured together and one of which is provided with a longitudinally extended groove, an attaching string or like device extended longitudinally of the tag between said layers and located in said groove, and reinforcing devices extended transversely of said tag between said layers on opposite sides of the attaching string or device and across the groove, substantially as described.

30 2. A tag of the character described, comprising layers of paper or like material se-

cured together and one of which is provided with a longitudinally extended groove, an attaching string or like device extended 40 longitudinally of the tag between said layers and located in said groove, and a reinforcing device extended transversely of said tag between said attaching string or device and said grooved layer and extended 45 into the groove of the latter, substantially as described.

3. A tag of the character described comprising layers of paper or like material secured together, an attaching string or the 50 like extended longitudinally of the tag between said layers, and a reinforcing device extended transversely of said tag adjacent said attaching device and between said layers, said reinforcing device consisting of 55 an independent flexible element.

4. A tag of the character described comprising layers of paper or like material secured together, an attaching string or the 60 like extended longitudinally of the tag between said layers and a plurality of reinforcing devices extended transversely of said tag adjacent said attaching device and between said layers, said reinforcing devices consisting of independent flexible 65 elements.

In testimony whereof, I have signed my name to this specification in the presence of two subscribing witnesses.

CHARLES B. TEWKSBURY.
